KEY PUNCH

Lincoln M. Keefe, Springfield, Mass.

Application February 28, 1935, Serial No. 8,682

21 Claims. (Cl. 164—112)

This invention relates to improvements in key punches and has for an object the provision, in a key punch, of a record carriage which may be manually set to position any horizontal row in the record in alinement with the punches.

A further object of the invention is the provision, in a key punch, of a settable carriage and means for temporarily moving the carriage to another setting.

10 Another object of the invention is the provision, in a key punch, of a carriage which may be set with any horizontal row in the record in alinement with the punches and an operative lever having a visual indicator associated therewith by means of which the carriage may be moved to another position temporarily and adapted to automatically return to the original setting when the lever is released.

Still another object of the invention is the provision, in a key punch, of means for disabling the mechanism at a point between the keys and the punches during the time the carriage is being moved from one setting to another, the disabling means being rendered ineffective as the carriage comes into registration in any desired setting. This makes it impossible to punch a hole in the record in any other than the normal index positions.

Still a further object of the invention is the provision, in a key punch, of a carriage which may be adjusted for different widths of record cards and which is provided with a member engaging the top edge of a record and tending to force the bottom of the record into intimate contact with the carriage.

Another object of the invention is the provision, in a key punch, of means between the keys and the punches for imparting motion from the keys to the punches regardless of the relative location of the keys and the punches.

Still another object of the invention is the provision, in a key punch, of manually operated means accessible from the outside of the machine for returning to the normal position any of the punches which may stick.

A further object of the invention is the provision, in a key punch, of a settable record carriage, a visual indicator operatively connected thereto, means for temporarily setting the carriage for punching in another field of either a higher or lower order than the original field, and spring means for returning the carriage to the original setting regardless of whether the temporary set was of a higher or lower order.

55 A still further object of the invention is the

provision, in a key punch, having a carriage adapted to be set in any one of a plurality of fields and a visual indicator designating the fields, of an attachable or detachable visual indicator containing further designations in the various fields.

Other objects of the invention will be apparent to those skilled in the art.

Referring to the drawings:

Figure 1 is a front elevation of the new and improved key punch;

Figure 2 is a sectional drawing along the line 2—2, Figure 1;

Figure 3 is a top view parallel to the carriage and taken along the line 3—3, Figure 2;

Figure 4 is a rear view, partly broken away, showing the arrangement of the parts of the new and improved key punch;

Figure 5 is an end view of a portion of the new and improved key punch showing details of the drum, the hand lever and mechanism controlling the locking and unlocking of the carriage;

Figure 6 is an elevation partly in section of the drum shown in Figures 3 and 5; and

Figure 7 is an elevation, partly in section, taken along the line 7—7 of Figure 6 and showing the interrelation between the registration plate and the return dogs and springs.

Figure 8 is an enlarged view showing details of the key action.

A stepped member 20, together with end plates 21 and 22, form the main frame of the machine. The stepped plate is provided to carry the keys which will presently be described.

A plate 23 secured to the stepped plate 20 and the end plates 21 and 22 is provided with a cut away portion 24 and forms a support for a plate 25. The plate 25 is provided with an elongated depression 26.

A multiple die plate 27 is secured to the plate 25 and has a plurality of dies 28 communicating with the elongated depression 26 whereby portions cut out from the records may be discharged.

A punch supporting member 29 is secured to the plate 23 in any suitable manner; for example, by means of screws 30; at each end thereof, the spacing apart of said screws being preferably wider than the widest record which the punch is capable of handling.

The supporting member 29 carries a shaft 31 which pivotally carries a plurality of punch actuating levers 32. The levers 32 are each provided with a tongue 33 which engages a notch 34 in a punch 35.

The punches 35 are supported in a block 36 which might be termed a stripper.

When the levers 32 are moved about the pivot shaft 31 in a counterclockwise direction, as viewed in Figure 2, the tongues 33 engaging notches 34 in the punches 35 propel the punches into the dies 28.

A metallic block is secured to the supporting member 29 and carries spring means for returning the levers 32 to normal. This block is provided with a plurality of holes 38, one for each of the levers 32. Each hole carries a plunger 39, and spring 40. The upper end of each hole is closed by means of a screw 41. The pressure of each spring 40 is conveyed to its associated lever 32 by means of a plunger 39. The tension on the plunger 39 may be adjusted by means of the screw 41.

A transverse member 42 extends from the end plate 21 to the end plate 22. A substantial portion of the member 42 is hollowed out to form a receptacle for the metallic block 43. This block is retained in position by means of a plurality of set screws 44.

The block 43 is provided with a plurality of holes each containing a plunger 45, one plunger being provided for each lever 32. The lower ends of the holes in the block 43 have secured thereto conduits, one of which is designated by the numeral 46. The plungers 45 each have secured thereto a positive driving flexible means. In the present embodiment this flexible means is a close wound continuous spring 47.

The stepped plate 20 is provided with a plurality of keys, one of which is designated by the numeral 48. Each key 48 is provided with a shank 49 and a shouldered portion 50. A bushing 51 secured into the plate 20 secures the key in operative relation thereon. The shouldered end 50 of the key has a cavity 52 formed therein, and a plunger 53, similar to the plunger 45, engages the cavity 52 and transmits motion from and to the key.

The plungers 45 and 53 are provided with reduced end portions, not shown, which are threaded in a pitch matching the convolutions of the spring 47 so that they may be screwed into the ends of these springs.

The conduits, one of which is designated by the numeral 46, in addition to having one end secured to the block 43, have the other end secured to the interior of the stepped plate 20 in the following manner:

The conduit 46 passes through a bushing 54, 55 and terminates with the plunger 53 in cooperative relation to the shouldered portion 50 of the key. The conduit is retained in this position by the clamping action of the bushing 54 when the same is screwed into the plate 20.

Due to the fact that the close wound spring 47 is confined in the conduit 46, motion may be directly imparted from one point to another without any appreciable lost motion and through any angle. In view of this the positions of the keys 48 relative to the positions of the punch actuating levers 32 are immaterial and this form of construction has advantages over lever and gear linkages of the prior art in that the mechanism is greatly simplified and the final form of the device is not limited by the type of mechanism imparting motion from the keys to the punches.

A bottom plate 55 is secured to the stepped plate 20 and to the end plates 21 and 22, thereby forming a closure for the bottom of the device and stiffening the structure.

The record carriage, generally designated by the numeral 56, consists of a substantially rectangular plate 57 having a rectangular opening 58 formed therein so that the carriage can be moved relative to the punches and their associated mechanisms.

The plate 57 has secured thereto on the rear surface thereof, a rack 59 and a rack 60. A gear 61 meshes with teeth in the rack 59 and a gear 62 meshes with teeth in the rack 60. These gears are carried on a shaft 63 which is suitably journaled in the end plates 21 and 22 so that when the shaft 63 is rotated the motion is transmitted to the plate 57 through the gears and racks and thereby the carriage is moved up or down.

The operation of this shaft and the carriage motions will be presently described.

The plate 57 also has secured thereto on the rear face thereof, preferably adjacent to the racks 59 and 60, metallic angles 64 and 65. These angles are provided with a series of preferably rectangular notches 66. A slidable shaft 67 is supported by the end plates 21 and 22 and has a faced portion milled off to form a rail 68 of substantially rectangular form adapted to engage any of the notches 66. The rail portion 68 of the shaft 67 is provided with a notch adjacent to each of the angles 64 and 65. One of these notches is designated by the numeral 69, see Figure 3.

The rail 68 retains the carriage in any setting (according to which notch 66 is engaged thereby) and the carriage can only be moved when the notches 69 are in line with the notches 66. The method of actuating the slidable shaft 67 in connection with the moving of the carriage will presently be described.

The carriage 56 is provided with lands 70 and 71 for the records to align precisely therewith and for guiding the records into the spaces between the die plate 21 and the stripper block 36. A stop plate 72 is secured on one side of the land 70 and serves as an abutment for the end of the record to position its vertical columns in line with the punches. A stop plate 73 is positioned adjacent to one side of the land 71. The stop 73 has an angular foot 74 which is secured to the plate 57 by means of a screw 75. The screw 75 passes through a slot 76 formed in the plate 57 and the stop 73 may be set a greater or lesser distance from the stop 72 (this movement being limited by the length of the slot 76) to accommodate different widths of records.

The carriage 56 carries a plate 77 which has end portions 78 and 79 embracing preferably rectangular shafts 80 and 81. A rectangular sleeve 82 is secured to the shaft 80 forming a shoulder for limiting the upward movement of the shaft. A similar sleeve 83 is secured to the shaft 81 in the same manner and for the same purpose. The shafts 80 and 81 are secured to a spring plate 84 in any suitable manner. For example, by means of screws 85, one of which is shown dotted in Figure 1. The rear end of the spring plate 84 is secured to the plate 77 so that when the curved or front end of the spring plate 84 is raised the rectangular shafts 80 and 81 are moved upwardly endwise until the portions 82 and 83 come in contact with the end portions 78 and 79.

A suitable bottoming plate for the records, designated by the numeral 86, is secured to the lower end of the plate 57. When a record is inserted into the carriage its bottom edge comes

in contact with the plate 86, and its ends are positioned by the stop plates 72 and 73.

When a record is inserted in the carriage the spring plate 84 is raised as above described and when released the portions 82 and 83 contact with the upper surface of the record, thereby insuring the registration of the bottom of the record with the surface of the plate 86.

The plate 77 is provided with shouldered stud screws 87 and 88 which project through vertical slots 89 and 90 formed in the plate 57 so that the plate 77 may be adjusted vertically for records of different heights, nuts 91 and 92 being provided to secure the plate 77 in any desired setting.

The shaft 63, carrying the gears 61 and 62 above referred to, has a sleeve 93 splined or keyed thereto. The sleeve 93 has secured thereto a hub 94. The hub 94 is provided with a keyway 95. The sleeve 93 has a shouldered and a threaded reduced portion 96. A nut 97 secures a portion of the hub 94 against said shouldered portion.

The hub 94 has formed integral therewith a drum generally designated by the numeral 98. The drum 98 has a radial portion 99 which terminates in the hub 94. It also has a cylindrical portion 100 which is parallel to and spaced apart from the sleeve 93. The cylindrical portion 100 has formed integral therewith an outwardly extending radial section 101 which serves as a visual indicator as will presently be described.

An indexing plate 102 is pivoted on the sleeve 93 and is movably secured to the end plate 22 by means of screws 103 and 104 extending through slots 105 and 106 respectively in the plate 102.

The indexing plate 102 is provided with a plurality of notches 107 which correspond to the horizontal rows of index points in the records and each notch will cause the record to be positioned with one of its horizontal rows in registration with the punches.

A plurality of holes 108 are formed in the index plate 102 each hole being adjacent to one of the slots 107. The functions of these holes will presently be described.

A spring plunger 109 is carried by a bracket 110 secured to the end plate 21. The plunger 109 is provided with a tongue portion 111 adapted to engage any of the notches 107 and thereby to block the index plate 102 in any position, according to which notch is engaged. The bracket 110 is provided with a pointer 112, in line with the tongue 111, and adjacent to the radial portion 101 of the drum. The pointer 112 forms a portion of a visual indicator. The other portion of the visual indicator is formed on the outer surface of the radial portion 101 in the manner shown in Figure 3. The lines indicate the various index positions of the horizontal rows in the records and the numbers on the lines designate those rows. For instance, when the pointer 112 is in line with the line upon which the "2" is positioned it indicates that the horizontal "two" row of the records is in line with the punches.

The sleeve 93 is provided with a portion having a larger diameter and having slanting sides, which forms a cam. This cam is generally designated by the numeral 113. This cam engages a device for disabling all of the keys so that no perforations may be made in the record unless the record is in accurate registration with the punches. This mechanism consists of, referring to Figures 2 and 4, pivoted arms 114 and 115 carried on a shaft 116 which is journaled in the end plates 21 and 22. A bar 117 is secured to the

upper ends of the pivoted arms 114 and 115. A spring 115 has one end connected to the arm 115 and the other end connected to a pin 116 in the end plate 22, for holding this mechanism in the normal position shown in dotted lines.

When the drum 98, together with the sleeve 93 and its cam 113, are moved to the right, as shown in Figure 6, which is to the left as shown in Figure 4, the cam 113 engages the pivot arm 115 and moves it slightly in a clockwise direction as viewed in Figure 2, or outwardly as viewed in Figure 4, thereby positioning the bar 117 immediately above the extensions 118 forming an integral part of the levers 32. The drum and the sleeve shaft together with the cam must be moved in the manner described before the carriage can be moved to another position. The cam 113 continues to engage the pivot arm 115 until the carriage is set at another accurate index position and a movement of the drum to its normal position disengages the cam from the pivot arm 115 thereby allowing the bar 117 to return to the position shown dotted in Figure 2 which is its normal position, after which the keys are again enabled to actuate the punches.

The index plate 102 has secured thereto an overhanging extension 119 which overhangs the flanged portion 101 of the drum. This overhanging extension 119 is provided with a registering pin 120 which engages a hole 121 formed in the flanged portion of the drum. The flanged portion of the drum also has a keyway formed therein which is adapted to be engaged by a key 123. It is preferable to make this key in the form of a roller. The open face of the drum is provided with a registration pin 124 which is adapted to register with any of the holes 108 as will presently be described. The radial portion of the drum 98 has secured thereto an annular ring 125. This ring is of substantially larger diameter than the cylindrical portion 100. The slideable shaft 67 extends through the end plate 22 and carries at its outer end a lever 126. The lever 126 has formed therein a slot 127 which straddles and rides the ring 125 at all times so that any movement of the drum 98 lengthwise along the shaft 63 will be imparted to the slideable shaft 67.

A lever 128 is secured to the shaft 67 and is provided with a hole which is at all times in engagement with a guiding pin 129 located in the end plate 22. This lever and pin arrangement prevents the shaft 67 from rotating but permits it to slide freely as the position of the drum 98 is changed.

The hub 94 has secured thereto a ring 130 provided with sockets 131 and 132. A lever 133 has a portion thereof in the form of a ring 134 and an end portion 135 the tip of which is made in the form of a ball 136. The ring portion 134 is provided with pivot screws 137, 138 which pivotally engage the sockets 132 and 131 respectively. The ball 136 is positioned between sectors 139 and 140. These sectors are spaced apart by sleeves one of which is designated by the numeral 141 and they are spaced apart from the end plate 22 by sleeves one of which is designated by the numeral 142, the sleeves and sectors being secured to the end plate 22 by means of bolts 143 and nuts 144. The lever 133 is provided with a suitable handle 145.

When the operator engages the handle 145 and presses the same to the right as viewed in Figures 1, 3 and 6, the drum 98 together with the sleeve shaft 93 is moved to the right whereupon

the cam 113 causes the key action to be disabled as above described. By this movement the registering pin 120 is disengaged from the hole 121, the key 123 is disengaged from the keyway 122 and as the drum is moved further to the right the registration pin 124 engages a hole 108. At the same time the movement of the drum is imparted to the shaft 67 through the medium of the lever 126. This aligns the notches 69 in the rail 68 with the angles 64 and 65 so that the carriage is now free to move and the operator may release the index plate 102 by raising the spring plunger, whereupon the carriage may be moved to any desired setting by rotating the handle 145 to a higher or lower index point as indicated on the visual indicator 101.

When the desired setting is obtained the spring plunger 109 may be released and the tongue 111 is allowed to engage another notch 107. Having obtained the desired setting the drum 98 must be returned to its normal position before the keys can be operated.

A spring 146 surrounds the sleeve shaft 93 and bearing against the inner end of the hub 94 tends to return the drum to its normal position. As the drum returns to its normal position the shaft 67 returns to its normal position with the rail 68 engaging notches 66 in the angles 64 and 65 and at the same time the cam 113 is disengaged from the pivot arm 115 allowing the bar 117 to move out of the way of the extension 118 so that the keys can now actuate the punches.

From this it can readily be seen that the carriage may be set to punch holes in any horizontal row in the records.

Assuming that the horizontal rows represent months in which it is desired to record activities in, for example, the various departments of a department store, by setting and locking the carriage for any horizontal row in the record the data for the month represented by said row may be very rapidly perforated into the records. However, it has been found that occasionally the carriage must be moved to another horizontal row in the record either above or below the one in which most of the perforations are being placed. It was therefore necessary to devise some means for temporarily moving the carriage to another position so that one or more punching operations could be effected and to have the carriage automatically return to its original setting after these "out of the ordinary" punching operations have been completed.

An arm 147 is provided with a hub 148 which is journaled on the sleeve shaft 93. The arm 147 is provided with a stud 149 to which is secured one end of a preferably flat spring 150. The other end of the spring 150 is secured to a stud 151 carried by the index plate 102.

The index plate 102 also carries a stud 152. The drum 98 has secured thereto, in the interior thereof, a stud 153. The studs 152 and 153 clear each other radially and they are both parallel to the shaft 93. The arm 147 has a flat portion 154 which normally engages both the studs 152 and 153. A second arm 155 is provided with a hub 156 journaling on the sleeve shaft 93. This arm carries a stud 157 to which one end of a flat spring 158 is secured. The other end of the spring 158 is secured to the stud 151.

The arm 155 is provided with a straight portion 159 which engages the studs 152 and 153. The straight portion 159 contacts the studs 152 and 153 on the right hand sides thereof as viewed in Figure 7, and the flat portion 154 con-

tacts these studs on the left side as viewed in Figure 7. The spring 150 is so arranged that when the arm 147 is rotated counterclockwise, as viewed in Figure 7, the spring winds up; and when the arm 155 is moved clockwise, as viewed in Figure 7, its spring 158 is wound up. The arms 147 and 155 normally contact the studs 152 and 153 under an initial tension.

Now, with the carriage set to perforate in one horizontal row of the records as above described for the purpose of entering activities during any month, for example, and assuming that the carriage is set to perforate in the horizontal "5" row in the records, suppose it is found necessary to make one perforation in the "8" row, the handle 145 is moved to the right, as viewed in Figures 1 and 3, and thereby the drum 98 moves to the right to a point where the registering pin 120 is disengaged from the hole 121 and the key 123 is disengaged from the slot 122. The movement is continued until a point is reached where the drum can be rotated. However, the registration pin 124 must not enter any of the holes 108 because in this instance the plunger 109, its tongue 111 and the index plate 102 are not disturbed. This movement of the drum through the medium of the ring 125 and the lever 126 moves the shaft 67 to a point where notches 69 in the rail 68 permit the carriage to move (the slots 69 being of such width that the carriage is permitted to move with the drum in the position just described).

By moving the handle 145 upwardly the drum may then be rotated until the index line for the "8" row indicated on the flange 101 is in line with the pointer 112. When this point is reached the lever is moved further to the right so that the registration pin 124 goes into a hole 108 corresponding to the "8" position after which a punching operation may be effected in the horizontal "8" row in the record.

During the rotation of the drum just described, the stud 153 causes the rotation of the arm 147 and thereby increases the tension on the spring 150. As soon as the punching operation in the "8" row, just described, is completed the carriage must return to the "5" row where the main punching operations are being carried out. Therefore the handle 145 is released and the spring 146, acting endwise against the interior of the drum, disengages the registration pin 124 from the hole 108 and as soon as this occurs the spring 150 pulls the arm 147 back to its normal position (for example, from the dotted position shown in Figure 7 to the position shown in solid lines) after which the spring 146 continues to move the drum to the left (Figure 6) until the key 123 reengages the keyway 122 and the pin 120 reengages the hole 121, the carriage has returned to its original setting and punching operations may then be resumed.

Assuming that the carriage is set for punching operations in the "5" row and it is desired to move the carriage to a row having a lower index position value, for example, the "2" row, the handle 145 would be moved to the right, Figures 1, 3 and 6 as above described and when the registering pin 120 is disengaged from the hole 121 and the key is disengaged from the keyway 122 the handle would then be moved downwardly thereby rotating the drum 98 in a clockwise direction as viewed in Figures 5 and 7 in which case the stud 153 working against the surface 159 would rotate the arm 155 in a clockwise direction thereby winding up the spring 158.

As soon as the "2" on the visual indicator comes in line with the pointer 112 the handle is moved further to the right so that the registration pin 128 will engage one of the holes 108 in the index plate 102. This hole, of course, would be the one representing the horizontal "2" row in the record. While the handle is held in this position punching operations may be effected in the "2" row after which the handle may be released and the carriage allowed to return to the original setting for carrying on further punching operations in the "5" row.

A shaft 160 is journalled in the end plates 21 and 22 and one end of this shaft extends through the end plate 21 and has secured thereto a lever 161 which is provided with a handle 162. A cross pin 163 is carried by the shaft 160 adjacent to the end plate 21. A pin 164 is secured to the interior of the end plate 22 and a spring 165 is secured to the pin 163 and to the pin 164. This spring tends to hold the shaft in its normal position with the pin 163 engaging a stop (not shown).

The mid portion of the shaft 160 is slotted and has secured thereto a metallic angle 166. This angle is of such length that it spans all of the levers 32. When the shaft 160 is rotated by means of the lever 161 and handle 162 through an arc the angle 166 engages the outer ends of the levers 32 and thereby if a punch 35 gets stuck in a die 38 it may be released by the operation of the lever 161.

As the punching operations go on the punchings pass through the dies 28 and fall out via the depression 26.

A suitable back plate 167 is secured to the end plates 21 and 22 by means of screws 168 and thereby incloses the mechanism.

The drum 98 is provided with spring loaded clips 169 and 170 so that a paper strip 171 may be clipped to the drum. This strip 171 may carry legends or other representations of departments which carry "seasonal" goods, or it may carry any other designations desired.

Strips, one of which is shown at 172, are provided adjacent to the keys 48 and carry numerals indicating the columnar positions of the punches. For example, the lower right hand punch as viewed in Figure 1 is indicated as adapted to perforate in the 76th column of the record. These designations may be used, in some cases. In other cases it has been found expedient to attach to the keys removable buttons designating the name of the department or any other designation desired. One of these removable buttons is indicated by the numeral 173 designating the hat department.

Although a single embodiment of the invention is shown and described herein it is obvious that many changes may be made in the device without departing from the spirit of the invention as set forth in the following claims.

What is claimed is:

1. In a key punch, a frame, a die located on one portion of said frame, a punch in cooperative relation to said die, a lever pivotally supported on said frame and operatively associated with said punch, a key spaced apart from said die and supported on another portion of said frame, means between said key and said lever for transmitting motion from the former to the latter, a rigid conduit enclosing said means and defining a path for said motion, spring means acting against said lever for withdrawing the punch from the die and returning the lever and the

key to their respective normal positions, and a manually operable member adapted to engage said lever to withdraw said punch from the die in case of failure of said spring means.

2. In a punching machine, a plurality of dies, a punch for each of said dies, means for selectively propelling said punches into and out of said dies, a record carriage adapted to support a record in operative relation to said punches and dies, means for setting and locking said carriage in any desired position relative to the punches whereby a series of punching operations may be effected, means including a manually operable lever for temporarily moving said carriage whereby punching operations may be effected in another portion of the record, and mechanism and spring means associated with said lever for returning the carriage to said first setting when said lever is released.

3. A device as claimed in claim 2 in which an indicator is associated with the manually operable lever for visually indicating the index value of the setting.

4. In a punching machine, a frame, a plurality of dies supported on said frame, a punch for each of said dies, a plurality of keys carried by said frame and spaced apart from said punches, means for transmitting motion from each individual key to an associated punch, a record carriage movably carried on said frame and adapted to support a record in operative relation to said punches and dies, means for setting and locking said carriage in any desired position relative to the punches, said means including a rotatable shaft geared to said carriage and a manually operable lever for moving said shaft, and means also operable by said lever for moving said carriage on said frame without disturbing said means for setting and locking the carriage.

5. In a punching machine, a frame, a plurality of dies supported in alignment on said frame, a stripper block parallel to and spaced apart from said dies, a plurality of punches slidably supported in said stripper block and adapted to cooperate with said dies, a lever operatively connected to each of said punches, a plurality of keys carried by said frame and spaced apart from said levers, operative linkage between said punches and said levers for transmitting motion from each individual key to its associated lever and punch, a record carriage movably carried on said frame, means for setting and locking said carriage in any one of a plurality of positions on said frame, means interposed between said carriage and said setting and locking means for temporarily moving the carriage away from a locked position while keeping the main carriage holding means in locked position, and spring means for returning said carriage to its locked position when the interposed means is released.

6. A device as claimed in claim 5 in which the carriage is provided with angular strips having notches formed therein and a shaft slidably mounted in said frame is provided with portions adapted to engage said notches for retaining the carriage in any desired setting relative to the dies, and in which the punching mechanism is disabled during the carriage movement, and enabled when one of said portions engages a notch.

7. In a punching machine having a frame, a plurality of punches and dies, and selective means for propelling said punches into and out of said dies; a record carriage movably supported on said frame, a pair of racks secured to said car-

riage, a rotatable shaft supported in said frame, a plurality of gears on said shaft meshing with said racks, an index plate pivotally carried on said shaft, said plate having registration notches formed therein corresponding to index positions in the record relative to said punches, an actuating member secured to said shaft and adapted to engage said index plate, means carried on said frame for engaging any of said notches in the index plate, and means interposed between said plate and said member for temporarily moving the carriage to other index positions than the one indexed by said plate, said last means including spring means for returning said carriage to the position indexed by the plate when the means for temporarily moving the carriage is released.

8. In a punching machine having a frame, a plurality of punches and dies, and selective means for propelling said punches into and out of said dies; a record carriage movably supported on said frame, a pair of racks secured to said carriage, a rotatable shaft supported in said frame, a plurality of gears on said shaft meshing with said racks, an index plate pivotally carried on said shaft, said plate having registration notches formed therein corresponding to index positions in the record relative to said punches, a drum secured to said shaft, a flange formed integral with said drum carrying graduations corresponding to index positions in the records and having a keyway formed therein and spaced apart from said graduations, a key carried by said index plate and adapted to engage said keyway when the drum is in a normal position, locking means carried on said frame and engaging one of the notches of the index plate, and a lever operatively connected to said drum and adapted to move the same longitudinally along said shaft to disengage said key from said keyway after which the drum may be rotated to move the carriage.

9. A device as claimed in claim 8 in which the drum is provided with two springs acting in opposite directions and so arranged that when the drum is rotated in either direction the tension of at least one of the springs is increased thereby causing the shaft to rotate in an opposite direction and to return the carriage to its original position on the frame when the lever is released.

50 10. A device as claimed in claim 8 in which the carriage carries a serrated strip and in which the frame carries a slideable member adapted to engage one of said serrations for locking the carriage in any desired registration, said member engaging and disengaging said serrations in accordance with the longitudinal movement of said drum.

11. A device as claimed in claim 8 in which the shaft is also provided with a cam, and a member carried on said frame is engaged by said cam during the movement of the carriage and engages said propelling means thereby preventing the punches from operating during the movement of the carriage.

65 12. In a machine for punching cards in which perforations along one dimension represent different classes of information and perforations along another dimension represent data in the respective classes, a single row of key operated
70 punches disposed parallel to the perforations along said first dimension, a frame supporting said punches and the keys associated therewith, a card carriage on said frame, means for adjusting said carriage parallel to said second dimension and
75 locking the same in position for perforating in a

single line along said first dimension, and means including a manually operable lever and a self-centering return mechanism for moving said carriage from its locked position for perforating data of other values or classes, said return mechanism being adapted to return the carriage to said first locked position.

13. In a key punch including punches, keys, a frame and a carriage movable on said frame, indexing means for setting said carriage a definite relation to said punches whereby data of any given index value may be recorded, means for disassociating said carriage from the set indexing means and moving the same to a setting of an index value different from said first value, and means associated with said second means, and operable when said second means is released, for returning said carriage to its original setting, regardless of whether the index value of said second setting is greater or less than said first setting. 10 15 20

14. In a punch for perforating records, a frame, a multiple die and punches therefor supported on said frame, means for selectively actuating said punches, a record carriage movably mounted on said frame, a rotatable shaft carrying mechanism engaging said carriage, an index plate pivoted on said shaft, a member on said frame adapted to engage said plate, a hollow drum keyed to said shaft and longitudinally movable thereon, a stud secured to the index plate and extending into the hollow of said drum, a stud in said drum parallel to and spaced apart from said first stud, both of said studs being parallel to said shaft and normally in line radially within said drum, an arm pivoted on said shaft and normally contacting one side of both of said studs, a second arm pivoted on said shaft and normally contacting the opposite side of both of said studs, spring means associated with one of said arms adapted to be wound up when the same is moved in one direction, spring means associated with the other of said arms adapted to be wound up when the same is moved in a direction opposite to said first direction, and rotatable means to rotate the drum in either direction thereby causing said second stud to rotate one of said arms and wind up the spring means associated therewith; said spring means being adapted, through the medium of one of said arms and one of said studs, to rotate said shaft and bring said carriage to a normal position defined by the initial setting of the index plate.

15. A punching machine according to claim 14 in which the spring means associated with said arms comprises flat spiral springs each having one end connected to an arm and the other ends connected to a second stud carried by the index plate.

plate. 16. A punching machine according to claim 14 in which the means for selectively actuating the punches includes, manually operable keys carried on said frame and spaced apart from the punches, and individual means for transmitting motion from each key to a corresponding punch is provided and confined within a rigid conduit defining a path for said motion. 60 65

17. A punching machine according to claim 14 in which the drum is provided with a graduated flange carrying an indexing pin, an indexing hole, and an indexing keyway; in which said index plate is provided with an extension overhanging said flange and carrying a registration pin which normally engages said indexing hole, and a key which normally engages said indexing keyway; in 70 75

which a spring embracing said shaft within the hollow of the drum holds the drum in a normal position, and in which a lever is associated with the drum for moving it longitudinally against 5 said last spring to disengage said pin and said key from the flange and for rotating the drum to move the carriage after such disengagement.

18. A punching machine according to claim 14 in which the drum is provided with clips by means 10 of which a strip bearing designations may be applied to the drum.

19. In a punching device for perforating records, a die, a plurality of punches for said die, means for moving said punches into and out of said 15 dies, a frame supporting said punches and said dies, a carriage for said records movably supported on said frame, means for setting and locking said carriage on said frame, balanced resilient means between said carriage and said frame, and 20 means for temporarily moving said carriage from a set and locked position and unbalancing said resilient means during each temporary movement.

20. In a punching device for perforating records, a die, a plurality of punches for said die, means for moving said punches into and out of said dies, a frame supporting said punches and said dies, a carriage for said records movably supported on said frame, mechanism for moving said carriage on said frame, a locking member, a pawl 5 on said frame adapted to engage said member for locking said carriage on the frame in any desired setting, and balanced spring means interposed between said member and said mechanism thereby permitting said mechanism to be operated to move said carriage in either direction from a locked position on said frame and at the same time unbalancing said spring means. 10

21. A punching device according to claim 20 in which said mechanism includes a manually operable lever which when released returns to a normal position while the carriage returns to its original setting under the urge of said spring means 15 while balancing itself. 20
